UNITED STATES PATENT OFFICE.

JOHN C. STUTZ, OF ALBUQUERQUE, NEW MEXICO.

AUTOMATIC SASH PLOWING AND BORING MACHINE.

Application filed February 14, 1925. Serial No. 9,258.

This invention relates to new and useful improvements in woodworking machines, and particularly to machines for treating sash stiles for the reception of the sash cords.

5 The principal object of the invention is to provide a machine which automatically feeds sash stiles from a hopper or magazine, and which bores one or more sockets in the edge of the stile, and plows a groove or grooves for the purpose of the reception of the sash cord.

Another object is to provide a machine of this character wherein the operations of boring and plowing are performed automatically, as the stile is carried through the machine.

20 Another object is to provide means whereby the carrier belt is adapted to travel continuously, whereby to permit action of the boring and plowing tools on the work, without interference of the belt, means being also provided for holding the work while the belt continues.

Another object is to provide a carrier chain which is equipped with means for automatically moving the boring means into operative position, and to subsequently move the plowing tools into cutting engagement with the stile.

30 Other objects and advantages will be apparent from the following description when taken in connection with the accompanying drawings.

In the drawings:

35 Figure 1 is a side elevation of a machine made in accordance with the present invention.

Figure 2 is an end elevation of the same.

Figure 3 is a top plan view of the machine.

40 Figure 4 is a vertical transverse sectional view on the line 4—4 of Figure 3.

Figure 5 is a vertical longitudinal sectional view on the line 5—5 of Figure 3, passing through the boring bit table, or bed.

45 Figure 6 is an enlarged top plan view of a portion of the carrier chain, showing the bit tripping roller, and the plowing tool actuating cam.

Figure 7 is a vertical transverse sectional detail view on the line 7—7 of Figure 1, showing the connection of the cord 93 and the bed 85.

Referring particularly to the accompanying drawings, 10 represents a frame which is approximately L-shaped in cross section, and includes the horizontal base portion 10', and

the vertical portion 10", said latter portion having a longitudinal V-shaped groove 11 in its upper face, as clearly seen in the cross sectional views. One end of the vertical portion 10" is formed with a longitudinal extension 12, which is provided with suitable brackets 13 for supporting the transverse shaft 14. The other end of the portion 10" is cut away, as shown at 15, and on this portion, and on the base portion, in transverse alinement, are the brackets or bearings 16, which support the transverse, main drive shaft 17. On the base 10', intermediate the ends thereof, are mounted the bearing brackets 18, which support the transverse shaft 19. On the shaft 14 are the belt wheels 20 and 21, which are of different sizes. On the shaft 17 are the belt wheels of different diameters, and indicated at 22, 23 and 23'. 70 On the shaft 19 are the differently sized belt wheels 24, 24' and 25. On the base 10', adjacent the other end thereof, is a transverse shaft 26, supported in brackets 27, mounted on said base. On the shaft 26 are the different sized belt wheels 28 and 29. Engaged around the belt wheel 22 is a drive belt 30, which receives power from any suitable source, not shown. Engaged around the belt wheels 23' and 24' is a drive belt 31, 80 while a drive belt 32 is engaged around the wheels 25 and 28. A drive belt 33 is engaged around the belt wheels 20 and 29. On the end of the vertical portion 10", are mounted the bearing brackets 34, which 85 support the shaft 35, carrying the wheel 36. Both of the wheels 21 and 36 are peripherally grooved and have the bottom walls of said grooves V-shaped in conformity with the groove 11, of the frame. It will be noted 90 that the shafts 19 and 26 extend transversely through the vertical portion of the frame.

Mounted on one side of the vertical portion of the frame are the vertically alined pairs of brackets 37 and 38, respectively, 100 supporting the vertical shafts 39 and 40. Fixed on the upper ends of these shafts are the plowing tools or saws 41 and 42, respectively, the former being of greater thickness than the latter, because of the fact that the 105 said former saw is adapted to cut a groove of greater width than the latter saw. On the shaft 40 are fixed the belt wheels 43 and 44, the former of which is driven by the belt 45, from the belt wheel 23. On the other 110 shaft 39 there is fixed a belt wheel 46, which is driven from the belt wheel 44 by the belt

47, whereby both of the shafts 39 and 40 will be rotated in unison. Adjacent each of the shafts 39 and 40 are the vertically aligned pairs of apertured ears 48 and 49, and disposed vertically through the pairs of ears, respectively, are the threaded shafts 50 and 51. The intermediate portion of the shaft 50 is received vertically through the intermediate portion of an arm 52, and a fastening pin 53 engaged through the arm and shaft whereby to secure the parts together. One end of the arm 52 is formed with a yoke 54 vertically through the arms of which is loosely disposed the upper portion of the shaft 40, while the other end of the arm has longitudinally extending and longitudinally adjustable extension 55. Carried by the outer end of the extension 55 is a transversely adjustable member 56, and rotatably supported in the outer end of this member 56 is a roller 57, to which more particular mention will be made later herein. The shaft 50 is provided with adjusting nuts 58 on the upper and lower ends, above and below the ears 48, whereby said shaft may be adjusted vertically, to raise and lower the arm 52, whereby to position the saw 42 properly with respect to the work. The shaft 51 is disposed vertically through the intermediate portion of an arm 59, and has adjusting nuts 60 on the upper and lower ends, above and below the ears 49. One end of the arm 59 is formed with a yoke 60', the arms of which loosely and vertically receive the shaft 39 therethrough. The other end of the arm carries the adjustable extension 61, on which is adjustably mounted the member 62, which has the roller 63 in its free end. The arm 59 is adapted to swing on the shaft 51 to move the shaft 39, and its saw 41 toward and away from the work.

Engaged around the grooved wheels 21 and 36 is the work carrying chain, designated as a whole by the numeral 64. This chain is made up of a plurality of links 65, properly pivoted together, and each having a longitudinally extending V-shaped rib 66, on its lower or inner face for engagement in the groove 11 of the frame. The width of the chain is approximately the same as the width of the wheels 21 and 36, whereby the portions of the links, at opposite sides of the rib, ride on the peripheries of the flanges of said wheels, while the rib is disposed therebetween. Mounted on the table, or upper face of the vertical portion 10", is a longitudinally extending and transversely adjustable work guiding fence 67, said fence being disposed in close proximity to one edge of the carrier chain. Secured to corresponding sides of a consecutive series of links of the chain, are the outwardly extending plates 68, the endmost of which have their outer end portions cut off obliquely, as shown at 69, for proper engagement with

the rollers 57 and 63, successively, as the chain progresses. Mounted on the frame, and overlying the upper lap of the carrier chain 64, are the arms 70, and rotatably supported on each of the arms is a spring pressed roller 71, which is adapted to be held in downward pressing engagement on the upper face of the work, as the work is moved along with the carrier chain. Extending horizontally outward from rearmost of the links which carry the plates 68, is a stub shaft 72, and rotatably supported on this shaft is a roller or wheel 73, while on the upper face of one of the links, a short distance rearwardly of the wheel 73, is a vertically extending lug 74. Mounted on the frame below the extension 12, is a transverse rock shaft 75, one end of which is provided with a vertical operating lever 76, while the other end is provided with a radial weighted arm 77, carrying a roller 78 on its outer end for engagement with the upper lap of the drive belt 33, for the purpose of stopping and starting the carrier chain.

Supported on the frame, in proper spaced relation above the carrier chain, are the vertical channel members 79 and 80, which form the magazine and receive the stiles to be treated. These members 79 and 80 are adjustable on the frame to accommodate stiles of different lengths, as shown at 81, while each of the members includes an adjustable portion 82, which is movable with relation to the other part, to accommodate stiles of different widths. It will be noted that the lower ends of the members 79 and 80 are disposed a certain distance above the face of the carrier chain, such distance being approximately that of the thickness of a stile to be treated, and whereby a single stile may rest on the chain and be readily moved from beneath the pile of stiles, by the lug 74 of the carrier chain.

Supported for vertical adjustment on one side of the vertical portion of the frame of the machine, is a bracket 83, and formed in the upper face of this bracket, transversely of the said frame, is a dove-tailed groove 84, in which is slidably disposed the bevel-edged table or bed plate 85. Properly supported on this bed 85 are the parallel shafts 86, carrying intermeshing gears 87, and in the end of each of the shafts, adjacent the side of the chain 64, is formed a chuck 88, for the reception of a bit 89, said shafts and bits being arranged obliquely with relation to the chain, whereby to bore sockets in the side face of a stile at an angle with respect to the stile. Supported on the frame, adjacent the carrier chain, and opposite the magazine, is an upright 90. Pivotedly supported in the upper end of this upright is one portion of an angle lever 91, the lower end of the vertical arm of which is disposed in the path of travel of the roller 73, whereby

to cause the lever to be rocked, as the carrier chain moves, in the operation of the machine. Mounted on the side of the frame is a grooved roller 92, and secured at one end to the free or outer end of the horizontal arm of the lever 91, is a flexible element 93, which may be a cord, wire, chain, or the like, the other end of said element passing through an opening 94, in the frame, and being secured to an adjustable eye-bolt 95, carried by the bed 85. Thus, as the roller 73 engages the lower end of the vertical arm of the lever 91, said arm will be rocked on its pivot with the result that the flexible element will draw the bed 85 toward the chain to engage the bits with the edge face of the stile. Also carried by the forward end of the bed 85 is a pair of arms 96, each of which carries a forwardly projecting pin 97 for engagement in the edge face of the stile, whereby to hold the stile against movement, as the chain continues to travel forwardly, said chain easily sliding beneath the stile. This operation takes place while the stile is at the bottom of the magazine, and at the proper interval preceding the engagement of the lug 74 with the end of the stile. The forward speed of the carrier chain is commensurate with the speed of the bits, whereby when the roller 73 has snapped past the arm of the lever 91, the bits have completed their boring operation in the edge face of the stile. The arms 96 are resiliently supported whereby to yield, to a certain extent, as the bed 85 moves forwardly toward the stile. Slidable through the frame of the machine, and adjustable through an apertured lug 98, on the bed 85, is the before-mentioned bolt or rod 95, a coil spring being disposed on the rod, and bearing against the said lug 98, and the side face of the frame, said spring being compressed as the bed moves inwardly, and serves to push the bed outwardly, at the completion of the boring operation, and when the roller 73 has passed the arm of the lever 91, as clearly seen in Figure 7.

On the outer end of one of the bit shafts 86 there is secured a belt wheel 100, which is driven by the belt 101, from the belt wheel 24, and whereby the bits are kept in constant rotation, ready for action on the stile when advanced thereto.

Upon the completion of the boring operation on the stile, the lug 74 engages the rear end of the lowermost stile, or that stile which has been bored, and carries same along on the face of the chain. When the advanced end of the cam plates strikes the roller 57, this roller is pushed away from the side of the frame, with the result that the arm 52 is rocked and the saw 42 pressed into cutting engagement with the edge of the stile. The chain, being in constant motion, carries the stile along, whereby the saw

cuts a channel or groove in the edge face of the stile. When the rearmost of the plates 68 has passed the roller 57, the saw will be removed from the stile, by means of the spring 102, disposed between the yoke 54 and the side of the frame. As the chain 64 moves onward the foremost of the plates 68 engages with the roller 63 and rocks the saw 41 into engagement with the edge face of the stile, whereby to plow a groove of greater width in the stile face. When the rearmost of the plates 68 has passed the roller 63, a spring 102, between the yoke 60 and the frame, swings the saw away from the stile. The boring and plowing operations having thus been completed on the stile, said stile is removed or discharged from the chain, as said chain passes around the wheel 21.

At approximately the instant that the saw 42 has completed the plowing of the narrow groove, another roller 73 has engaged the angle lever 91, to cause the advance of the bed 85, and the boring of the next stile, which has dropped onto the chain 64, from the magazine. Thus, while one stile is being plowed, another stile is being bored, with the result that the operation is continuous, the stiles being arranged in a line on the chain, and being successively operated upon by the bits and saws, to be discharged from the far end of the chain.

When it is desired to stop the carrier chain, the operator grasps the lever 76 and rocks the rollered arm 77 upwardly, whereupon the belt 33 will become slack, and the chain 64 ceases movement. Reverse movement of the lever 76 tightens the belt 33 and sets the chain 64 in motion.

What is claimed is:—

1. A woodworking machine including a constantly moving carrier, boring means movable toward and away from the carrier for operation on a piece of work on the carrier, means on the boring means for engagement with the work to hold the same stationary with respect to the carrier, means operable by the carrier while the work is thus held for advancing the boring means into engagement with the work, and means for withdrawing the boring and holding means whereby to release the work to the carrier.

2. A woodworking machine including a constantly moving carrier, boring means movable toward and away from the carrier for operation upon work on the carrier, means for moving the boring means toward the work on the carrier, means on the boring means for stopping the work independently of the carrier, means on the carrier for actuating the moving means, and means for moving the boring means from the work after the carrier means has passed said moving means, whereby to release the

- work for continued movement by the carrier.
3. A woodworking machine including a constantly moving carrier, means for depositing a single piece of work on the carrier, boring means movable toward and away from the carrier for action upon work on the carrier, a trip element operatively connected with the boring means for moving the latter toward the work, means on the carrier for engaging and moving the trip element to advance the boring means to the work, means on the boring means for holding the work while the carrier continues to move therebeneath, means for moving the boring means away from the work upon release of the trip element from the carrier means, and means on the carrier for moving the work from the depositing means only upon completion of the boring operation.
4. A woodworking machine including a constantly moving carrier, a work holding magazine supported above the carrier in position to deposit single pieces of work on the carrier successively, a boring means mounted for slidable movement into engagement with the piece upon deposit thereof on the carrier, means operable by the carrier for advancing the boring means to the work, means on the boring means for holding the work while the carrier continues to move beneath the work, and until the boring operation is completed, means for automatically moving the boring means from the work, and means on the carrier for engaging and moving the work from the magazine when the boring means has been withdrawn therefrom.
5. A woodworking machine including a carrier, means for depositing work on the carrier, means for boring a face of the work,

resilient means for normally holding the boring means away from the work, means operable by the carrier for moving the boring means into engagement with the work, a plowing means rockable into and out of engagement with the work, and means on the carrier for rocking the plowing means into engagement with the work.

6. A woodworking machine including an endless carrier, a magazine supported in position to deposit a piece of work on the carrier, boring means movable into and out of engagement with the work, a rock lever mounted adjacent the boring means and operatively connected therewith, a projection on the carrier for engagement with and rocking of the lever to move the boring means into engagement with the work, and resilient means for moving the boring means away from the work after the said projection has become disengaged from the lever.

7. A wood working machine including an endless carrier, a magazine supported in position to deposit a piece of work on the carrier, boring means movable toward and away from the work, plowing means movable toward and away from the work, means on the carrier for moving the boring means into engagement with the work and having means for holding the work against movement with the carrier, until the completion of the boring operation, means on the carrier for engaging the work to carry same to the plowing means, and means operable by the carrier for moving the plowing means into engagement with the work.

In testimony whereof, I affix my signature.

JOHN C. STUTZ.
